UNITED STATES PATENT OFFICE.

ERNEST DIDCOTE, OF WOKING, ENGLAND, ASSIGNOR TO ADVERTISING MACHINES LIMITED, OF LONDON, ENGLAND.

PICTURE-DISPLAYING APPARATUS.

Application filed December 23, 1924, Serial No. 757,599, and in Great Britain January 8, 1924.

My invention relates to picture displaying apparatus of the class wherein groups of curtain rollers are mounted at opposite ends of a supporting frame, and a traveller, moving intermediate these groups, withdraws and replaces individual rollers from the groups at the ends of its path, and unwinds their curtains to display them as it recedes from the groups and rewinds the displayed curtains as it approaches the groups.

The objects of my invention, among others, are to provide, in a picture display apparatus, a group of curtain rollers disposed in spaced relation and rotatable about a common axis, means for retaining said curtain rollers in spaced relation, and means for preventing accidental displacement of said curtain rollers from the aforesaid retaining means; to provide means adapted to secure the rollers against accidental displacement during their reciprocal transit while unwinding and winding their curtains; and to afford positive, smooth and quiet operation of the apparatus. The foregoing and further objects as hereinbelow more particularly specified are attained by the mechanism illustrated in the accompanying drawings forming part of this specification and in which:—

Figure 1 is a front elevation partly broken away of the display apparatus as a whole,

Figure 2 is an end elevation of Figure 1.

Figure 3 is a fragmentary section of Figure 1 taken on line 3—3 looking in the direction of the arrows,

Figure 4 is a vertical section taken on line 4—4 of Figure 3, looking in the direction of the arrows,

Figure 5 is a detail of the curtain roller,

Figure 6 is a detail of the drum disc,

Figure 7 is a diagrammatic representation of the curtain rollers,

Figure 8 is a detail of twin roller modification,

Figure 9 is an enlargement of a detail of Figure 2,

Figure 10 is a sectional elevation taken on line 9—9 of Figure 9,

Figure 11 is a plan view of Figure 10, and

Figures 12 and 13 are diagrammatic illustrations of an operation in connection with the traversing mechanism,

Figure 14 is a plan view and Fig. 15 is an end view of the part positioning the curtain rollers during transit,

Referring to the drawings, the frame of the apparatus is formed in two parts 1 and 2 secured together by distance pieces 3 and straps or caps 4 and cross bars 5 of which one is shown in Figure 2. Cross bars 6 serve to connect the legs of each part of the frame as shown. So-called drums 7 and 8 are secured to the top members of the frame as by legs 9 and straps 10 shown in Figure 3. Similar drums 11 and 12 are secured to the cross bars 6 in like manner. Channel members 13 and 14 are connected to extensions 15 of the upper and lower drums and pulleys 16 are mounted on the upper extensions for a purpose hereinafter described. Further channel guides 17 are secured by stays 18 at each side of the apparatus also hereinafter described. The arrangement above described forms a substantially rigid structure.

The curtain rollers 19 as shown, are formed in two groups of six each, one above and one below and are mounted so as to travel in annular grooves in the drums 7 and 8, 11 and 12 respectively. The method of mounting the rollers in the drums is as follows. Referring to Figures 3, 4 and 5 the drum 8 is provided with a flange 20 to form a housing for the bearing 21 in which a driving shaft 22 is journaled. The drum is also provided with annular flanges forming a groove or race 23. A disc 24 is keyed to shaft 22 adjacent the drum and is slotted at 25, see Figure 6. The spindle 26 of each curtain roller passes through one slot into the groove or race 23 and is fitted with a shoe or skate 27 upon which is mounted two anti-friction rollers 28. The arrangement is such that when the disc 24 is rotated the curtain rollers are moved round the groove or race in the drum. The arrangement with regard to drums 7, 11 and 12 is similar but in some cases the shoes or skates may be dispensed with in drums 7 and 11 and the annular grooves therein reduced in size to receive just the bare spindles of the squared ends of the curtain rollers.

Shaft 22 projects beyond bearing 21 and is fitted with one element 29 of a Geneva movement. The lower driving shaft is similarly fitted on the opposite side of the machine. The co-acting elements 30 of each Geneva movement are mounted upon stub shafts 31 journaled in the frame.

The shoe or skate 27 provides a ready

means of overcoming the friction caused by the torsional strain of the spring upon the curtain roller spindle keeping the tension necessary for the rewinding of the curtain 5 upon the spring roller when it is being returned to its position after having been exposed to view.

The drive for the upper and lower shafts 22 and the drum discs is from a motor—not 10 shown—coupled to the worm 32 with which the worm wheel 33 meshes. This worm wheel is mounted on a shaft 34 journalled in the frame and this shaft carries sprockets 35 and 36. Chain 37 transmits motion to the 15 lower shaft 31 which actuates the lower Geneva movement and intermittently rotates the lower shaft 22. Chain 38 transmits motion to a shaft 39 fitted with sprockets 40 and 41 the latter of which transmits motion 20 through a chain 42 to the sprocket 43 on the upper stub shaft 31 thereby driving the upper Geneva movement and intermittently rotating the upper shaft 22 and its drum discs. Both the upper and lower shafts 22 25 are moved step by step in synchronism.

One end of each curtain 44 on the rollers 19 is secured to a rod or lath 45, see Figure 7, 30 detachably secured in openings or slots 46 in the disc at each end, see Figure 6. When therefore a roller is removed from the carrying drums and drawn up or down by the travelling device hereinafter described their curtain is exposed.

The mechanism for drawing the curtain 35 rollers up and down for changing them will now be described. Chain 42 trained about sprockets 41 and 43 is duplicated on the opposite side of the machine as shown at 47, 48 and 49. Travellers 50 and 51 are arranged to 40 move up and down the sides of the apparatus and for this purpose carry rollers 53 running in the vertical channel members 13 and 14 respectively. Slide members 54 mounted in horizontal guides 55 in the travellers each 45 carry a further roller 56 and are provided with vertical slots 57 for a purpose referred to hereinafter.

In order to move the travellers, the end of one arm 58 of a bell crank lever (see Figures 50 9, 10 and 11) is keyed to the chain 42 as by pins 59, this lever being pivoted in bearings 60 in the traveller 51 and having at the end of its other arm 61 a roller 62 engaging in the vertical slot 57. When the chain is in motion 55 it will be seen that so long as the pins are being carried on a vertical length of chain intermediate the sprockets 41 and 43 the traveller and slides are carried up or down with it as a rigid unit. When, however, the pins commence 60 to ride around one or other of the sprockets, the bell crank must likewise commence to turn on its axis. Such turning being impossible so long as the slide is held fixed by its roller 56 being in the channel 65 guide 14, horizontal branches 63 are pro-

vided in the channel at those points occupied by the rollers when pins enter upon a sprocket (see Figures 12 and 13). The bell crank can therefore turn by reason of the vertical slot 57 within which moves the roller 62 at the end 70 of its arm 61 and since the slide is free to move horizontally. Accordingly, when the pins enter upon a sprocket wheel, the roller 56 turns into a branch 63 and the traveller being thereby prevented from moving vertically, remains stationary in its uppermost (or lowermost) position.

The half-turn of the crank during the time the pins are on the sprocket, causes the slide to reciprocate horizontally and regain its initial position as the pins leave the sprocket. A similar cycle of operations occurs when the pins reach the other sprocket, the horizontal branch there issuing in the opposite direction 85 since the slide moves to the other side.

To prevent the rollers 53 carried by the traveller from entering into the branches when they pass the junctions, idle rollers 64 are mounted therein as shown.

Each traveller carries a block 65 whose upper and lower parts are shaped to fill gaps 66 (see Figure 3) in the drums, and each of these parts is channelled to receive and accommodate a skate 27. These parts of the block 65 may be regarded as removable sections of the drums and are herein thus referred to.

When the travellers are moved into their uppermost position the annulation of the grooves or races in the drums is completed and whilst temporarily at rest in this position as hereinbefore described the shaft 22 and its slotted discs are moved one step forward so as to transfer the picture roller and skate from the block 65 into the groove or race 23 and introduce a fresh one. This movement of the shaft 22 is effected by the engagement of a pin 59 with an element 67 of the Geneva movement which rocks the latter together with the element 30 through an angle of 180 degrees as it rides round the sprocket 43 and by means of the pin 68 whereby the element 29 is rocked through an angle of 60 degrees. As will be understood the operation is repeated at the lowermost 105 position of the travellers so that there are always two rollers carried in transit across the front of the apparatus, except during the period of changing rollers.

The travellers are counterbalanced by a 110 weight bar (not shown) suspended by cords or chains 69 over the pulleys 16 (see Figure 4).

The curtain rollers are positioned during 115 transit by means of a so-called H-piece 70 mounted on each traveller by means of a rod 71 in sleeve bearings so as to be capable of relative vertical movement. The H-pieces are secured to and interconnected by a strip or lath 72 which serves the purpose of cover- 120

ing the gap between the two rollers in transit. Recesses 73 in the H-pieces accommodate and position the spindles 26 of the rollers.

The longer arm 74 of a bell crank lever pivoted at 75 in the traveller engages by means of a pin 76 and slot 77 with the lath 72. The shorter arm 78 carries a roller 79 running in the channel guide 17 which is inturned at the ends as shown at 80 so that just before the traveller reaches its uppermost or lowermost position the lever is rocked and the long arm is depressed or raised respectively. This movement causes relative vertical motion between the H-piece and traveller so that the former as well as the lath 72 are arrested and kept clear of the drums during the changing of picture rollers.

An aperture 81 is provided in the lath 72 fitted with plain or coloured glass or other suitable material through which the light behind the pictures is projected.

It will be clear from the foregoing description that there are always therefore two rollers in the travellers progressively and alternately winding and unwinding their curtains in order to display and obliterate a picture or other device on one side only of the apparatus.

In order to display curtains on both sides of the apparatus simultaneously two rollers may be mounted in a common skate or shoe 68, see Figure 8 and the other parts of the apparatus correspondingly modified in a manner which it is not deemed necessary to describe. In this case each traveller carries

35 four rollers in transit.

I claim:—

1. Picture display apparatus comprising stationary drums, curtain rollers mounted in annular grooves therein, removable sections 40 in said drums, means operating intermittently, serving to bring the rollers in succession into the removable drum sections, and means for traversing said drum sections and the rollers therein back and forth across the apparatus.

2. Picture display apparatus comprising a stationary drum, an annular groove therein, a removable section in said drum; a plurality of curtain rollers, spindles terminating said 50 rollers and skates fitted to said spindles, the said skates being mounted in said groove and adapted to travel therein when the removable section is in said drum; means operating intermittently adapted to bring the rollers in succession into the removable section of the drum, and means for traversing said removable section and the roller therein into and out of the drum.

3. Picture display apparatus comprising stationary drums, curtain rollers mounted in annular grooves therein; a rotatable slotted disc adjacent the groove side of each drum; spindles upon said rollers engaging the slots in said disc, means for rotating said discs 60 step by step, whereby rotation of the discs

serves to move the curtain rollers around the annular grooves in the drums sections of said drums being separable therefrom and means including a traveller carrying said removable sections adapted to remove same from and to 70 restore same to, said drums in timed relation to the rotation of said discs.

4. Picture display apparatus including a stationary drum, a removable section therein, a traveller carrying said removable section 75 and adapted to move said removable section into and out of engagement with said drum, means for reciprocating said traveller comprising endless chains and driving pins thereon coacting with said traveller, means adapted to reverse the direction of travel of said pins, and means whereby the traveller is maintained stationary during the period the direction of travel of the driving pins is being reversed.

5. Picture display apparatus comprising stationary drums, removable sections in said drums, curtain rollers slidably mounted in annular grooves in said drums, a part of the groove in each drum lying within the removable section; a traveller carrying said removable sections and a slide therefor adapted to be reciprocated toward and away from said drums; means associated with said slide adapted to lock said traveller against movement while the said rollers are moving in said grooves, and means adapted to move said rollers into and out of said removable sections.

6. Picture display apparatus including stationary drums, removable sections in said drums, curtain rollers mounted in said drums, and means for moving said rollers about said drums and into and out of said removable sections; a traveller carrying said removable sections, and adapted to move said sections into and out of engagement with said drums, and to remove a section when a curtain roller is in said section; a member carried by said traveller and serving to position said roller 100 in transit; and means adapted to arrest the movement of said positioning member for predetermined intervals at the terminals of its reciprocation.

7. Picture display apparatus including a pair of oppositely disposed stationary drums at the upper end and a pair of stationary drums in vertical alignment respectively therewith at the lower end of the apparatus; a plurality of curtain rollers mounted in 115 guides in each pair of drums, and means adapted to cause said curtain rollers to move in a closed path about said drums; vertical guides extending from the lower to the upper drums; a travelling carriage vertically movable between said guides; means whereby said carriage engages a curtain roller at either end of its travel and transports said rollers up and down said guides; means for arresting the travel of said carriage at the ends of its travel 120 125 130

and for retaining said carriage at rest during the periods of movement of said rollers about said drums; and means for arresting the movement of the said rollers about said drums 5 during the periods of travel of said carriage.

8. Picture displaying apparatus including a pair of oppositely disposed stationary drums at the upper end and a pair of stationary drums in vertical alinement respectively therewith at the lower end of the apparatus; 10 a plurality of curtain rollers mounted in guides in each pair of drums and means adapted to cause said curtain rollers to move in a closed path about said drums; vertical 15 guides extending from the lower to the upper drums; a travelling carriage vertically movable between said guides; means whereby said carriage engages a curtain roller at either end of its travel and transports said rollers up and down said guides; a positioning member 20 on said travelling carriage adapted to locate a pair of curtain rollers during transit and means including a bell-crank lever carrying a roller and a guide in engagement therewith, 25 said guide having inclined end portions adapted to cause said positioning member to move relatively to said carriage; means for arresting the travel of said carriage at the ends of its travel and for retaining said carriage 30 at rest during the periods of movement of said rollers about said drums; and means for arresting the movement of the said rollers about said drums during the periods of travel of said carriage.
9. Picture displaying apparatus including a pair of oppositely disposed stationary drums at the upper end and a pair of stationary drums in vertical alinement respectively therewith at the lower end of the apparatus; 35 a plurality of curtain rollers mounted in guides in each pair of drums and means adapted to cause said curtain rollers to move 40

in a closed path about said drums; vertical guides extending from the lower to the upper drums; a travelling carriage vertically movable between said guides; means whereby said carriage engages a curtain roller at either end of its travel and transports said rollers up and down said guides; a positioning member 45 on said travelling carriage adapted to locate a pair of curtain rollers during transit and means including a bell-crank lever carrying a roller and a guide in engagement therewith, said guide having inclined end portions adapted to cause said positioning member to move relatively to said carriage; means for arresting the travel of said carriage at the ends of its travel and for retaining said carriage 50 at rest during the periods of movement of said rollers about said drums; means for arresting the movement of the said rollers about said drums during the periods of travel of said carriage, and means consisting of a strip of lath serving to screen the gap between rollers in transit, said lath being connected to and arrested with the said positioning member. 55

10. Picture display apparatus comprising in combination a supporting frame, upper and lower drums carried by said frame, curtain rollers mounted in annular grooves in said drums by means of skates fitted on the roller spindles, removable segments in said drums, rotatable discs with slots engaging with the roller spindles, driving mechanism 70 in intermittent engagement with said discs and adapted to rotate said discs step by step, travellers adapted to carry said removable drum segments, means for traversing said travellers back and forth between the said upper and lower drums, and means for temporarily arresting said travellers when adjacent said drums. 75

ERNEST DIDCOTE,
